UNITED STATES PATENT OFFICE.

JERROLD GAY BELCHER, OF ATHENS, OHIO.

DESIGN FOR A BOOK END OR SIMILAR ARTICLE.

Application filed February 29, 1924. Serial No. 8,778. Term of patent 7 years.

To all whom it may concern:

Be it known that I, JERROLD GAY BELCHER, a citizen of the United States, whose post-office address is 23 South Congress Street, in the city of Athens, county of Athens, and State of Ohio, have invented a new, original, and ornamental Design for a Book End or Similar Article, of which the following is a specification, reference being had to the accompanying drawing, forming part thereof.

Figures 1 and 2 are respectively perspective and side views of a book end showing my new design.

I claim:

The ornamental design for a book end or similar article as shown.

In witness whereof, I hereunto subscribe my name this 20 day of February, 1924.

JERROLD GAY BELCHER.

Witnesses:

DAGMAR PETERSON,
A. C. AHLBERG.
